HYDRAULIC HOIST

Ernest J. Shaffer, Tulsa, Okla., assignor of one-half to Daniel W. Shaffer, Hutchinson, Kans., and one-half to George W. Shaffer, Jr., Tulsa, Okla.

Application October 26, 1944, Serial No. 560,436

15 Claims. (Cl. 254—93)

1

This invention relates to hydraulic hoisting apparatus and particularly to a hydraulic draw works system for well drilling rigs.

A principal object of this invention is the provision of a hydraulic apparatus adapted to operate for the raising or lowering of loads and which has a wide range of flexibility in its operative movements.

Another object is the provision of a simplified draw works system for well drilling rigs which is fully hydraulically operated, which is highly flexible and of greatly simplified construction, and which will replace the more conventional drilling rig draw works systems having wire lines, sheave blocks, cable drums, multispeed transmissions, braking mechanism and power connections commonly employed in such systems.

A further object is the provision of a system and apparatus which is easy to control by the operator, which is comparatively simple in construction and fool-proof in operation.

Still another object is the provision of a hydraulic draw works system for use with well drilling rigs which is largely self-contained and adapted for easy portability from place to place as a part of a complete drilling rig.

Other and more specific objects and advantages of this invention will become apparent from the following detailed description when read in conjunction with the accompanying drawings which illustrate a preferred form or embodiment in accordance with this invention. It will be understood that various modifications and alterations of the details of this invention may be made within the scope of the appended claims, but without departing from the spirit of this invention.

In the drawings:

Fig. 1 is a side elevation of the hydraulic hoist device of this invention, shown in assembled relation as a part of a complete drilling rig and arranged therewith on a common base structure for purposes of ready portability;

Fig. 2 is a plan view of the base structure of the drilling rig showing the layout of the various elements of the rig on the common base;

Fig. 3 is a front elevation of the device of Fig. 1 showing particularly the arrangement of the parts of the hydraulic hoist and having some of the parts broken away for purposes of better illustration of its details;

Fig. 4 is an enlarged cross-sectional view of a detail of the device taken along line 4—4 of Fig. 3;

2

Fig. 5 is a skeletonized or schematic view of the principal elements of the hydraulic device;

Fig. 6 is a side elevation of the device as applied to a portable drilling rig, illustrating the manner of raising and lowering the hydraulic hoist members relative to the base structure; and

Figs. 7 and 8 are details of the pivoted connection between the hoist device and the base structures.

Referring to the drawings, the hydraulic hoist device, in accordance with this invention, arranged for use with a well drilling rig, is designated generally by the numeral 1, and is shown supported in a generally vertical position by a supporting frame, designated generally by the numeral 2. The supporting frame 2 includes a horizontally disposed base 3 of the skid type adapted for ready movement from place to place by a suitable transporting vehicle (not shown). 10 Mounted on base 3 are the usual power supply engine 4, mud pump 5, and rotary table 6 normally employed in rotary drilling rigs. The rig also includes the usual power shaft 7, driven from engine 4 by a power connection 8, and drivingly connected to the mud pump 5 by a power connection 9 and to a cat-head shaft 10, carrying a cat-head 10a, by another power connection 11. The rotary table drive shaft 12 is driven from the cat-head shaft 10 by still another driving connection 13. These several driving connections are of the conventional types, such as sprocket-and-chain connections or V-belt-and-pulley drives. The usual clutches are also provided in proper relation to the various drive connections to provide for engagement and dis-engagement of the several driven units with the power source.

Supporting frame 2, of which only one side is shown, the other side being substantially identical in construction, includes upright leg members 14 disposed on opposite sides of base 3 and spaced rearwardly from the hydraulic hoist 1. Suitable girts and braces 15 and 16, respectively, connect leg members 14 to the members of the hydraulic hoist. The structure thus formed is pivotally supported upon a sub-base structure which is rigidly attached to base 3 and includes rear leg supports 17 upon which the lower ends of leg members 14 rest when in upright position. The sub-base structure also includes a pair of trunnion cradles 18 rigidly mounted on opposite sides of base 3 and adapted to rotatively cradle hollow trunnions 19 to which are attached the lower ends of hollow legs 20 and 20a, upon which the hydraulic hoist device is mounted. Upwardly and rearwardly extending angle braces 21 provide

3

rigid bracing between trunnion cradles 18 and the upper ends of leg supports 17. Angle braces 22 connect hollow trunnions 19 to the lower ends of leg members 14 and are adapted to register with angle braces 21, when the hoist device and supporting frame are in the upright position. Suitable removable connecting means, such as bolts 23, rigidly connect braces 21 and 22 when the device and supporting frame are in the upright position, and are adapted for removal when the superstructure is to be lowered to a transport position. When assembled in the upright position, the hydraulic hoist and the supporting frame including the sub-base structure form a derrick mast of the usual generally pyramid shape.

The hydraulic hoist 1 comprises a pair of vertically extending cylinders 24 and 24a, supported on hollow legs 20 and 20a, respectively, and constructed of heavy metal tube or pipe adapted to withstand high internal pressures and other stresses normally developed therein under operating conditions. Cylinders 24 and 24a have internal bores 25 and 25a, respectively, and are provided at their upper ends with caps 26. Bore 25 communicates with the interior of its supporting hollow leg 20 through a passageway 25b. A piston rod 27, carrying a piston 27a on one end thereof, is reciprocably mounted in each of the bores 25 and 25a, the opposite ends of rods 27 extending upwardly out of the cylinders 24 and 24a through suitable openings in caps 26. The upper ends of piston rods 27 carry brackets 28 in which the ends of a cross head 29 are rigidly connected. Extending rearwardly from brackets 28 are U-shaped slides 30 which slidably engage with upwardly extending guide members 31, which are rigidly supported in their upright positions by vertical support columns 32 forming a part of the main support frame 2 by connection to leg members 14 by means of suitable girts and braces 33 and 34, respectively. A pinion shaft 35 extends transversely above cross head 29 between brackets 28 and the ends thereof are journaled in bearing supports 36 carried by brackets 28. A pinion 37 is mounted on pinion shaft 35 adjacent each end thereof and mesh with elongated racks 38 rigidly attached to the forward faces of guide members 31. Co-action of pinions 37 with their respective racks 38 serves to keep the piston rods 27 moving in unison during reciprocation, and maintains even distribution of the load carried by the piston rods 27 under all hoisting conditions.

Mounted in the center of cross head 29 is a universal joint connection 39 from which is suspended a hydraulic cylinder 40, by means of a connection 41 which acts also as a closure for the upper end of cylinder 40. A piston rod 42, carrying a piston 43, is reciprocably mounted in the bore of cylinder 40 and extends downwardly therethrough to the exterior of the cylinder through a bottom closure 44 connected to the lower end of the cylinder. A load connecting hook 45, of suitable and more or less conventional form, is hingedly attached to the lower end of piston rod 42 by means of a hinge pin connection 46. Hook 45 is adapted for connection to the drilling string or other loads to be raised and lowered in connection with drilling operations. As shown in Fig. 3, particularly, hook 45 is connected to the bail 47 of a water swivel 48 which, in turn, is connected in the usual manner to the Kelley rod 49 of a drilling string extending through rotary table 6 into the well beneath (not shown).

Hollow cross connections 50 and 51 provide

75

4

communication between the lower and upper ends, respectively, of cylinders 24 and 24a, the points of communication being, respectively, below and above the limits of reciprocation of pistons 27a. The bore of hollow leg 20a which supports cylinder 24a communicates through a flexible hose 52 with the lower end of the bore of cylinder 40 below the point of maximum downward travel of piston 43, and a pipe 53, supported along side hollow leg 20, communicates by means of a flexible hose 54 with the upper end of cylinder 40 above the point of maximum upward travel of piston 43. A second pipe 55, also supported along side hollow leg 20 communicates with cross connection 51.

A high pressure pump 56, preferably of the multi-stage centrifugal type, is mounted on base 3 and is driven from power shaft 7 by means of a suitable driving connection 57. The suction of pump 56 is connected at 58 with a tank 59 containing a supply of a suitable hydraulic fluid. The hydraulic fluid is discharged by pump 56 through a pipe 60 to a hollow supply header 61 which communicates through a nipple 62 with the interior of hollow trunnions 19 and thence with the bore of leg 20. A four-way control valve 63 is interposed in pipe 60 and has a branch connection 64 communicating with the lower end of pipe 55 which leads to cross-connection 51. A return pipe 65, for the return of fluid from the several hydraulic cylinders, is connected to another of the outlets of control valve 63 and leads back to tank 59. A second hydraulic fluid circuit includes a pipe 66 connected to discharge pipe 60 and to a second four-way control valve 67, from one outlet of which a pipe 68 connects to the lower end of pipe 53. Another outlet of valve 67 is connected by a pipe 69 to a second supply header 61a connected by a nipple 62a to the bore of hollow leg 20a, and a third outlet of control valve 67 connects through a branch pipe 70 with the return pipe 65. A pipe 71, having a control check valve 72 interposed therein, provides a continuous by-pass connection between discharge pipe 60 and tank 59. An operating handle 72a is used to adjust the rate of flow through check valve 72 and by-pass 71 to regulate the pressure on the system and the volume of fluid passing through control valves 63 and 67. A stand-by pump 73, driven from power shaft 7 by a drive connection 74, has a suction connection 75 to tank 59 and a discharge connection 76 to discharge pipe 60. A valve 77 is interposed in discharge connection 76 between stand-by pump 73 and discharge pipe 60 to permit cutting-in and out of pump 73 in the hydraulic supply circuit. Control valves 63 and 67 have their inlet and outlet connections and ports so arranged that at one position of their operating handles the valves connect one end of their connected cylinders to discharge pipe 60, while simultaneously connecting the opposite ends of the cylinders with return pipe 65.

With respect to the operation of the device, above described, reference should also be had to the schematic arrangement illustrated in Fig. 5, the more significant parts of which bear the same identifying numerals as are applied to the corresponding parts in the other figures.

Assume it is desired to withdraw the string of drilling tools from a well. Piston rods 27 and cross head 29 will be in the fully retracted position shown in solid outlines in Figs. 1 and 3. Piston rod 42 will be fully extended, as shown in solid lines in Fig. 5, it being assumed that the

upper end of the drilling string is momentarily at its lowest point above rotary table 6. Fluid pressure may be applied beneath piston 43 by transmission from pipe 68 through control valve 67, pipe 69, the bore of leg 28a and connection 52. At the same time fluid is released from above piston 43 through connection 54, pipe 53 and back through return line 65 to tank 58, these operations being effected by suitable manipulation of valve 67. The application of pressure beneath piston 43 retracts piston 42 in cylinder 40 raising hook 45 and the drilling string connected thereto. When this movement is completed, the portion of the drilling string so withdrawn may be broken-out in the usual manner and swung from the derrick while still attached to hook 45. This pipe handling operation is possible because of the flexible connection between cylinder 40 and cross head 29 provided by universal joint connection 39. These operations may then be repeated until the string is completely removed, or partially removed, as desired, from the well.

If, however, it is desired to withdraw a greater length of the string than is effected by the full stroke of piston rod 42, an additional length may be withdrawn after piston rod 42 has completed its retractive stroke, by then applying fluid pressure beneath pistons 27a in cylinders 25 and 25a and forcing the pistons and their connecting cross head upward for all or part of their stroke, cylinder 40 and its connected load being drawn up therewith for the additional distance represented by the stroke of piston rods 27. Fluid pressures for this operation will be supplied through the proper connections by suitable manipulation of control valve 63. Alternatively, if the shorter stroke only is desired, piston rod 42 may be left in extended position and pistons 27a moved to their extended positions, shown in dotted outlines in Fig. 3. Again, if the longer stroke is desired and the full power of all the hydraulic cylinders utilized at the same time, piston 43 may be retracted as described and pistons 27a extended, both operations being conducted simultaneously by suitable simultaneous manipulation of the control valves 63 and 67.

Any single one or any combination of these operations may be employed when running or pulling drill pipe, casing tubing or other tool strings. When drilling down, the operation may be begun by having pistons 27a in the fully extended positions and piston rod 42 in the fully retracted position, and allowing piston rod 42 to be extended and pistons 27a to be retracted under the weight of the string of drilling tools, pressure fluid being withdrawn simultaneously or sequentially from beneath the respective pistons during descent of the tools, or, if desired, pressure may be applied above the several pistons if it is desired to drill down under pressure greater than that of the weight of the tools alone.

These and all other operations conventionally required about a drilling rig for hoisting and for some of the drilling operations may all be performed by suitable manipulation of the combination of hydraulic cylinders and pistons, arranged as described. It will be seen that great flexibility of operation is afforded, and the many advantages of smooth operation, close control of speeds, hoisting and braking pressures and other characteristics of hydraulic systems may be utilized to the fullest extent.

The flexible connection provided by the uni-

versal joint connection 39 between the cross head member 28 and its depending cylinder 40, which is ordinarily the most actively used element of the device, permits this centrally suspended cylinder to engage in all of the conventional operations normally performed with the conventional traveling blocks, wire line connection to the crown blocks, draw works drums and the like. Since cylinder 40 may swing in all directions from its connection to the universal joint, the cylinder will absorb all of the vibrational and swaying movements normally incident to the various hoisting and drilling operations about a drilling rig.

The provision of the rack-and-pinion connection between piston rods 27 and supported guides 31 is especially useful and important in insuring fully unified movement of the side pistons throughout all operations and even distribution of the load on the pistons. Otherwise, unequal loading, for one reason or another, of the side pistons, might cause these pistons to move at unequal rates and result in destructive or injurious binding or jamming between the relatively moving parts.

The areas of the several pistons may be made of any suitable dimensions depending upon the loads to be handled and the manner of distribution desired. The areas of pistons 27a are ordinarily made equal to provide for equal distribution of the loads thereon, and their combined area will be sufficient to carry the full load for which the device is designed. Piston 43 is ordinarily made to have an area equal to the combined areas of pistons 27a, since in many operations, the cylinder 40 will be required to carry the full load on the device.

Cylinders 24 and 24a and hollow legs 28 and 28a constitute the front legs of the derrick structure in which much of the load, including the shock load ordinarily occurring during operation, is absorbed in the hydraulic cushion inside the cylinders on which the pistons are cushioned, thereby increasing the life of the structure and its members.

Fig. 6 illustrates the manner in which the hydraulic cylinders may be employed, without assistance from outside agencies, for raising and lowering the hoist device and the supporting structure. To lower the structure from the upright position to the lowered position, shown in dotted outlines in Fig. 6, a wire loop 78, or other similar connection, is suitably connected at one end to the rear of the sub-base structure and the other end is hooked to hook 45, piston rod 42 being in its fully retracted position. Fluid pressure is then released from beneath piston 43 and applied above the piston, causing piston rod 42 to be extended. The mast may be constructed so that the center of gravity is forward of the trunnions 19, causing the structure to tilt forwardly about trunnions 19 as pivots. Or the structure may be manually pushed or pulled past its center of gravity in order to start it on its downward movement. The fluid pressures on the opposite sides of piston 43 are then controlled through suitable manipulation of control valve 67 to allow the structure to be lowered of its own weight by the controlled extension of piston rod 42. The structure may be raised back to its upright position by applying fluid pressure so as to retract piston rod 42, which acting through the anchorage of hook 45 to the sub-base structure, will hydraulically raise the structure to the upright position.

Any desired speeds of operation or fluid pressures may be employed in effecting the various operations performed by the hydraulic device in accordance with this invention, by suitable manipulation and adjustment of valves 63 and 67 and check valve 72. Any suitable type of hydraulic fluid may, of course, be employed, and many other and varied operations in addition to those specifically described, may be performed by the combination of hydraulic cylinders and pistons heretofore described.

From the foregoing it will be seen that this invention provides a simplified form of hydraulic hoist, which is particularly adapted for use with well drilling rigs, which is comparatively inexpensive to construct and operate, which is simple in operation, and which eliminates all of the many heavy, complicated and expensive hoisting mechanisms and devices employed in connection with conventional drilling rigs.

What I claim and desire to secure by Letters Patent is:

1. In a well drilling rig, a hydraulic draw works system comprising, in combination with a base member, a pair of laterally spaced hydraulic lifts vertically supported on said base member, a cross connection between said pair of lifts reciprocable thereby, means operatively associated with said cross connection for synchronizing the reciprocating movements of said pair of lifts, a third hydraulic lift suspended between said pair of lifts from said cross connection, a load connecting member reciprocably supported by said third lift, and means to supply actuating fluid to all of said lifts, said synchronizing means comprising a rack and pinion guide for each one of said pair of lifts, said pinions being carried on a common shaft extending transversely between the pair of lifts and rotatively supported thereon.

2. In a well drilling rig, a hydraulic draw works system comprising in combination with a base member, a pair of laterally spaced hollow leg members pivotally supported on said base member, a pair of laterally spaced hydraulic lifts vertically supported on said hollow leg members, a cross connection between said lifts reciprocable thereby, a third hydraulic lift disposed between said pair of lifts and swingingly suspended from said cross connection, a load connecting member reciprocably supported by said third lift, an actuating fluid circuit connected to said pair of lifts and including one of said hollow leg members in the circuit, a separate actuating fluid circuit connected to said third lift and including the other of said hollow leg members in the circuit, a common source of supply of said actuating fluid for both said circuits, and independently operable control means in each of said circuits.

3. In a well drilling rig, a hydraulic draw works system comprising in combination with a base member, a pair of laterally spaced hydraulic cylinders vertically disposed on said base member and pivotally connected thereto, an elongated frame connected to said pair of cylinders and adapted to pivot therewith on said base member, pistons reciprocably mounted in said pair of cylinders, piston rods connected to said pistons and extending upwardly from the upper ends of said pair of cylinders, a cross head connecting the upwardly extending ends of said piston rods and reciprocable therewith, a shaft extending parallel to said cross head and rotatably supported thereon, a pinion mounted on each end of said shaft, vertically disposed guide racks engaging with said pinions for constraining syn-

chronized movement of said piston rods, a third cylinder swingingly suspended between said pair of cylinders from said cross head, a third piston reciprocably mounted in the third cylinder and having a third piston rod connected thereto and extending downwardly from the lower end of said third cylinder, a load connecting member carried by the extended end of said third piston, an actuating fluid circuit connected to opposite ends of said pair of cylinders, a second actuating fluid circuit connected to opposite ends of said third cylinder, independently operable control means in each of said circuits, each of said control means being operable in its circuit to effect movement of the pistons responsive thereto in either direction at will, and a common source of supply of said actuating fluid for both said circuits.

4. In a well drilling rig, a hydraulic draw works system comprising, in combination with a base member and a derrick structure uprightly disposed on said base member, a pair of laterally spaced hydraulic lifts vertically supported in said derrick structure, a cross connection between said lifts reciprocable thereby, a third hydraulic lift disposed between said pair of lifts and swingingly suspended from said cross connection, a load connecting member reciprocably supported by said third lift, means to supply actuating fluid to all of said lifts, and independently operable means for controlling the actuating fluid to said third lift, whereby the latter may be actuated independently of the movements of said pair of lifts.

5. A hydraulic hoist comprising, a pair of laterally spaced hydraulic lifts, a cross connection between said lifts reciprocable by the joint movements thereof, a rack and pinion guide for each one of said pair of lifts associated with the cross connection, said pinions being carried on a common shaft extending transversely between the pair of lifts and rotatably supported thereon, a third hydraulic lift disposed between said pair of lifts, a universal joint member between said cross connection and said third lift, a load connecting member reciprocably supported by said third lift, and means to supply actuating fluid to all of said lifts, said means including separate control means for the fluid going to said pair of lifts and for the fluid going to said third lift to independently control the movement of the respective lifts.

6. In a well drilling rig, a hydraulic draw works system comprising in combination with a base member, a pair of laterally spaced hydraulic lifts vertically supported on said base member, a cross connection between said lifts reciprocable by the joint movements thereof, a third hydraulic lift suspended between said pair of lifts from said cross connection, a load connecting member reciprocably supported by said third lift, and means to supply actuating fluid to all of said lifts, said means including hollow cross connections between the lower and upper ends of said pair of lifts and control means for selectively actuating said pair of lifts and said third lift to independently control movement of the respective lifts.

7. In a well drilling rig, a hydraulic draw works system comprising, in combination with a base member, a pair of laterally spaced hydraulic lifts vertically supported on said base member, a cross connection between said pair of lifts reciprocable thereby, a third hydraulic lift disposed between said pair of lifts and swingingly suspended from said cross connection by a universal joint member, said universal joint closing the upper end of said lift, a load connecting member reciprocably supported by said third lift, and means to supply

actuating fluid to all of said lifts, said means including hollow connections between the lower and upper ends of said lifts.

8. In a well drilling rig, a hydraulic draw works system comprising in combination with a base member, an elongated frame pivotally mounted on the base member, a pair of laterally spaced hydraulic lifts vertically supported on said frame, a cross connection between said pair of lifts reciprocal thereby, means operatively associated with said cross connection for synchronizing the reciprocating movement of said pair of lifts, a third hydraulic lift suspended between said pair of lifts from said cross connection, a load connecting member reciprocably supported by said third lift, and means for supplying actuating fluid to all of said lifts whereby said lifts may be selectively operated.

9. In a well drilling rig, a hydraulic draw works system comprising in combination with a base member, an elongated frame pivotally mounted on the base member, said frame including hollow legs, a pair of laterally spaced hydraulic lifts vertically supported on said legs, a cross connection between said pair of lifts reciprocal thereby, means operatively associated with said cross connection for synchronizing the reciprocating movement of said pair of lifts, a third hydraulic lift attached to and suspended between said pair of lifts from said cross connection, a load connecting member reciprocably supported by said third lift, means for supplying actuating fluid to said pair of lifts through said legs, means for supplying an actuating fluid to the third lift whereby said lifts may be selectively operated.

10. In a well drilling rig, a hydraulic draw works system comprising in combination with a base member, a pair of laterally spaced hydraulic cylinders vertically disposed on said base member, an elongated frame connected to said pair of cylinders and adapted to pivot therewith on said base member, pistons reciprocably mounted in said pair of cylinders, piston rods connected to said pistons and extending upwardly from the upper ends of said pair of cylinders, a cross head connecting the upwardly extending ends of said piston rods and reciprocal therewith, a shaft extending parallel to said cross head and rotatably supported thereon, means mounted on each end of said shaft for constraining synchronized movement of said piston rods, a third cylinder swingingly suspended between said pair of cylinders from said cross head, a third piston reciprocably mounted in the third cylinder and having a third piston rod connected thereto and extending downwardly from the lower end of said third cylinder, a load connecting member carried by the extended end of said third piston, an actuating fluid circuit connected to opposite ends of said pair of cylinders, a second actuating fluid circuit connected to opposite ends of said third cylinder, independently operable control means in each of said circuits, each of said control means being operable in its circuit to effect movement of the pistons responsive thereto in either direction at will, and a common source of supply of said actuating fluid for both said circuits.

11. A fluid hoist including a mast member, a pair of hydraulic lifts each including a cylinder element and a piston element, means anchoring one element of each lift with respect to the mast member, means interconnecting the other elements of said pair of lifts including a cross member reciprocably responsive to movement of said elements, a third hydraulic lift including piston

and cylinder elements, one of which is connected with the cross member, load connecting means carried by the other element of the third lift, laterally arranged guide means on one of said members, laterally arranged rolling means on the other member and having engagement with said laterally arranged guide means, and means interconnecting said rolling means for synchronizing movement of said interconnected elements of the pair of lifts to maintain parallel relationship of said lifts.

12. A fluid hoist including mast and base members, a pair of hydraulic lifts each including a cylinder element and a piston element, an elongated frame connected to one element of each lift and adapted to pivot therewith on the base member, means interconnecting the other elements of said lifts including a cross member reciprocably responsive to movement of said elements, a third hydraulic lift including piston and cylinder elements, one of which is connected with the cross member, load connecting means carried by the other element of the third lift, laterally arranged guide means on one of the cross and mast members, laterally arranged rolling means on the other of said last named members and having engagement with said laterally arranged guide means, and means interconnecting said rolling means for synchronizing movement of said interconnected elements of the pair of lifts to maintain parallel relationship of said lifts.

13. A fluid hoist including mast and base members, a pair of hydraulic lifts each including a cylinder element and a piston element, an elongated frame connected to one element of each lift and adapted to pivot on the base member, means interconnecting the other elements of said lifts including a cross member reciprocably responsive to movement of said elements, a third hydraulic lift including piston and cylinder elements, one of which is connected with the cross member, the cylinder of the third lift being of a size substantially equal to both of said pair of lifts, load connecting means carried by the other element of the third lift, laterally arranged guide means on one of the cross and mast members, laterally arranged rolling means on the other of said last named members and having engagement with said laterally arranged guide means, and means interconnecting said rolling means for synchronizing movement of said interconnected elements of the pair of lifts to maintain parallel relationship of said lifts.

14. A fluid hoist including mast and base members, a pair of hydraulic lifts each including a cylinder element and a piston element, an elongated frame connected to one element of each lift and adapted to pivot on the base member, means interconnecting the other elements of said lifts including a cross member reciprocably responsive to movement of said elements, a third lift including piston and cylinder elements, one of which is pivotally suspended from the cross member, load connecting means carried by the other element of the last named fluid lift, laterally arranged guide means on one of the cross and mast members, laterally arranged rolling means on the other of said last named members and having engagement with said laterally arranged guide means, and means interconnecting said rolling means for synchronizing movement of said interconnected elements of the pair of lifts to maintain parallel relationship of said lifts.

15. In a well drilling rig including a derrick, a hydraulic draw works system comprising, in com-

bination with a base member, a pair of laterally spaced hydraulic lifts vertically supported by said base member, a cross connection between said pair of lifts reciprocable thereby, means operatively associated with said cross connection for synchronizing the reciprocating movements of said pair of lifts, a third hydraulic lift suspended between said pair of lifts from said cross connection, a load connecting member reciprocably supported by said third lift, and means to supply actuating fluid to all of said lifts, said means to supply actuating fluid to all of said lifts including separate control means for the fluid going to said pair of lifts and for the fluid going to said third lift to independently control the movements of the respective lifts.
